UNITED STATES PATENT OFFICE.

JAMES SWAN, OF SEYMOUR, CONNECTICUT.

DESIGN FOR A TOOL-HANDLE.

SPECIFICATION forming part of Design No. 28,230, dated February 1, 1898.

Application filed October 6, 1897. Serial No. 654,297. Term of patent 14 years.

To all whom it may concern:

Be it known that I, JAMES SWAN, a citizen of the United States, residing at Seymour, in the county of New Haven and State of Connecticut, have invented and produced a new and original Design for Tool-Handles; and I do hereby declare the following to be a full, clear, and exact description of the same, reference being had to the accompanying drawing, forming part thereof, in which the figure represents an elevation of a tool-handle embodying my design.

The leading feature of my design consists of a tool-handle having the surface of its gripping portion provided with rounded spiral ribs parallel with each other and oblique to the axis of the handle, said ribs and the spaces between them imparting to said gripping

portion the appearance of a spirally-fluted roll.

A denotes the gripping portion of the handle. The surface of the gripping portion is ornamented with a series of spiral ribs *a* with spaces *b* between them, the whole imparting to said gripping portion the appearance of a spirally-fluted roll, the ribs alternating with spaces.

What I claim is—

The design for a tool-handle substantially as shown and described.

In testimony whereof I affix my signature in presence of two witnesses.

JAMES SWAN.
